UNITED STATES PATENT OFFICE.

CARL KAEMPFER, OF WEST HOBOKEN, NEW JERSEY.

DETACHABLE CONNING-TOWER AND LIFE-BUOY.

1,188,179.

Specification of Letters Patent. Patented June 20, 1916.

Application filed December 14, 1915. Serial No. 66,741.

To all whom it may concern:

Be it known that I, CARL KAEMPFER, a citizen of the United States, and a resident of West Hoboken, in the county of Hudson and State of New Jersey, have invented a new and Improved Detachable Conning-Tower and Life-Buoy, of which the following is a full, clear, and exact description.

This invention relates to an improved type 19 of conning tower adapted for use especially in connection with submarine vessels.

Among the objects of the invention is to provide a conning tower in the nature of a buoy, the main portion of which is housed 15 normally within the outline of a submarine boat or its equivalent, but having a portion projecting sufficiently above the hull of the boat to provide means for an observer stationed therein to view in all directions along 20 or over the surface of the water, the main portion of the device being adapted, however, to be detached from its normal position and allowed to float to the surface of the water in the event of the stranding of 25 the vessel, or under other circumstances.

Another object of the invention is to provide a conning tower so connected to the submarine as to be despatched from the same to the surface of the water while the 30 submarine is located at any suitable distance below the surface, whereby observations may be made along or over the surface of the water at any time irrespective of the depth at which the vessel may be located below the 35 surface.

With the foregoing and other objects in view, the invention consists in the arrangement and combination of parts hereinafter described and claimed, and while the invention 40 is not restricted to the exact details of construction disclosed herein, still for the purpose of illustrating a practical embodiment thereof reference is had to the accompanying drawing in which the figure is a 45 vertical sectional view indicating a preferred embodiment of the invention in normal position in connection with a submarine boat.

Referring now more particularly to the 50 drawing, I show a rigid casing 10 of any suitable size or form secured rigidly in place

mainly within the hull 11 of the submarine or other vessel. The top of the casing is open and provided with a flaring flange 12. The bottom 13 of the casing is normally 55 closed, but is provided with a watertight guide member 14 having a packing gland 15 secured on its lower end and having a nipple 16 extending upwardly therefrom and surrounded by a rubber gasket 17 or the 60 like. The bottom 13 is also tapped and fitted with a pipe 18 which may be understood as representing means for pumping water out of the casing, means (not shown) being provided as usual for ejecting water from the 65 inside of the vessel. A trap door 19 is provided in connection with the bottom 13, the same being adapted to be held shut by a hasp 20 which may be operated from either the inside or the outside of the casing. 70

At 21 is indicated the body of the buoy having a downward conical projection 22 and any suitable number or location of transverse partitions or braces 23 and 24. These partitions may be regarded as floors separating the interior of the buoy into a plurality of compartments. An opening 23' in the floor or partition 23 and a similar opening 24' in the other floor serve to enable the men to pass from one compartment to the 80 other. A trap door 25 is provided in connection with the lower conical end of the buoy and is normally held closed by a hasp 26 of a character similar to the hasp 20 and adapted to be operated either on the inside 85 or the outside of the buoy. The lower end also is reinforced by side ribs 27.

At 28 I provide a rigid, strong shoulder fixed in place against the inner wall of the casing 10 not far below the open upper end thereof. This shoulder carries a packing gland or gasket 29 of a good quality of rubber or its equivalent, and a corresponding shoulder 30 is secured rigidly to the outside of the buoy, the same having a flaring or 95 frusto conical surface adapted to coöperate directly with the gasket 29 making a watertight seal or connection between the buoy and the casing.

A power cable 31 passes through the 100 packing gland 15, guide member 14 and gasket 17, and thence through the central

hole in the point member 32 at the apex of the buoy, and is thence guided through the hull 33 at the center of a bracing spider 34 adjacent the upper or base portion of the 5 buoy cone. The end of the cable is secured in any suitable manner for support upon a resilient seat or cushion 35 shown in the form of a coil spring seated in a socket 36 at the center of the spider. The point 32 is 10 made watertight by means of a packing gland 37 so arranged, however, as to permit a slight movement of the cable therethrough as allowed by the resiliency of the spring 35.

The power cable will be understood as 15 leading in any suitable direction within the hull of the vessel to any approved form of windlass or the like (not shown, but commonly used on shipboard), whereby the cable may be manipulated to control the 20 position or action of the buoy. Electric wires 38 may be carried within the cable for the purpose of providing means of communication between an operator in the conning tower portion of the buoy and the interior of the ship. A telephone 39 is shown 25 as an indication of means whereby such communication may be had and through which the man in the conning tower may convey such information to the commander of the 30 ship as to enable the maneuvering of the ship in effect to be directed from the conning tower.

The top of the conning tower is provided 35 with any suitable number or arrangement of watertight port holes 40 and is provided also with a normally closed exit 41 through which the men may make their escape when necessary or whereby access for other purposes may be had to the interior of the buoy.

40 With the parts arranged as shown in the drawing, the upper end of the buoy may constitute the equivalent of an ordinary conning tower of that type in which the observer may be stationed for direct view when 45 the ship is lying or operating at or adjacent the surface of the water. When, however, observation is to be made from above the surface of the water when the ship is at any considerable distance below the surface, the 50 buoy is permitted to rise from its normal position by releasing the cable 31 and permitting it to slip through the guide member 14, the lower or inner end of the cable, however, being controlled by the power devices 55 for the purpose of controlling the action of the buoy and returning it to position within the casing. Under ordinary condition the space below the coöperating shoulders 28 and 30 is empty of water whereby one or more 60 men may pass through the trap doors 19 and 25 into the buoy, such doors being thereafter closed and sealed as described. Since the lower portion of the casing is empty of water and the buoy supported above the

shoulder 28 is subjected to enormous water 65 pressure when the ship is below the surface, I provide a bypass 42 around the shoulders so as to permit water to pass from the outside to the inside of the casing, establishing equilibrium of pressures above and below 70 the packing shoulders. This bypass is provided with a normally closed valve 43 adapted, however, to be opened by any suitable means either within the buoy or within the hull of the vessel. When such equilibrium is 75 established, the buoy will be lifted by the buoyancy of the water in an obvious manner.

As a means of escape from a stranded submarine, for example, it is essential that the last man or group of men shall have means 80 of escape through the buoy. Such last group of men obviously will manipulate the power machinery to return the buoy to its normal place, pump the water from the sealed portion of the casing, and then enter the buoy 85 and lock themselves therein. In order for them, therefore, to open the valve 43 to admit water into the casing, I provide a pair 90 of contact rings 44 extending around the casing above the shoulder 28 or at suitable location to be bridged by a movable contact member 45 shown as housed normally within a pocket 46 within the buoy. When all is in readiness, the contact piece 45 may be forced outwardly against the force of the spring 95 47 bridging the contact rings and causing the valve 43 to be electrically operated. The electric devices just described are so constructed and arranged as to be neither damaged by nor interfere with the manipulation 100 of the buoy in the usual manner. When the power cable 31 is drawn downwardly to return the buoy to place, the point 32 will always be drawn into the open mouth of the casing and the reinforcement ribs 27 will 105 strengthen this portion of the buoy preventing damage thereto because of contact with the rim or flange 12 of the casing. The continued draft upon the cable will cause the buoy to be seated snugly in the normal position already described irrespective of the condition of the sea or the position or movement of the submarine.

I claim:—

In a submarine boat, the combination with 115 the hull, of a casing fitted thereto and having an open outer end, an annular shoulder secured to the inner surface of the casing adjacent its upper end, a detachable conning tower fitted normally within the casing and 120 having an annular shoulder coöperating with the aforesaid shoulder, forming a watertight joint excluding the water from the lower portion of the casing, a normally closed by-pass carried by the casing and 125 communicating with the inner surface thereof, above and below said shoulders, said bypass being normally closed, a pair of spaced

contact rings carried by the casing above the shoulders, a movable contact piece carried by the conning tower and projectable outwardly therefrom by pressure applied upon the inside of the conning tower to connect the contact rings, and means whereby when said rings are connected the by-pass

will be opened to admit water to the lower portion of the casing.

CARL KAEMPFER.
